UNITED STATES PATENT OFFICE.

JOHN MITCHELL BEAVER, OF FORT WORTH, TEXAS.

FOLDING UMBRELLA.

1,073,562.

Specification of Letters Patent. Patented Sept. 16, 1913.

Application filed March 25, 1913. Serial No. 756,782.

To all whom it may concern:

Be it known that I, JOHN M. BEAVER, a citizen of the United States, residing at Fort Worth, in the county of Tarrant and 5 State of Texas, have invented a new and useful Folding Umbrella, of which the following is a specification.

The present invention appertains to folding umbrellas, and relates particularly to an 10 improvement over the folding umbrella disclosed in my former application filed March 28, 1911, Serial Number 617,332.

It is the object of the present invention to provide a novel and improved foldable or 15 collapsible umbrella which may be collapsed into an extremely small compass, and which may be opened and closed with ease and despatch.

It is also the object of the present invention to improve certain details of construction in order to increase the efficiency and 20 utility of the umbrella.

With the foregoing general objects outlined, and with other objects in view, which 25 will be apparent as the nature of the invention is better understood, the present invention resides in the combination and arrangement of parts and in the details of construction hereinafter described and claimed, it 30 being understood that changes in the precise embodiment of the invention herein disclosed can be made within the scope of what is claimed without departing from the spirit of the invention.

35 The preferred embodiment of the invention has been illustrated in the accompanying drawing, wherein:

Figure 1 is a fragmental elevation of the framework of the umbrella, as open. Fig. 2 40 is an enlarged fragmental perspective illustrating the connection between the rib sections. Figs. 3 and 4 are sectional details taken on the lines 3—3 and 4—4 of Fig. 2, respectively. Fig. 5 is a side elevation of 45 the umbrella after being folded to its initial or primary folded position, parts being broken away. Fig. 6 is a view similar to Fig. 5, showing the ribs in their final collapsed or folded position, and showing the removable section of the staff detached. Fig. 7 is a perspective view of the tube. Fig. 8 is a fragmental view of the staff, the tube and runner being shown in section.

In carrying out the invention, reference 50 being had in detail to the drawing, the staff embodies the two sections or parts 1 and 2

which are preferably fashioned from wood although other materials may be employed. The upper section 1 forms the main section of the staff, whereas the section 2 provides 60 a detachable handle portion. A tube 3 is slidable on the lower end of the section 1, the section 1 terminating within the tube 3, and the upper end of the handle section 2 is reduced, as at 4, so as to fit within the 65 lower end of the tube 3. The reduced portion 4 is provided with a downwardly facing catch 5 engageable through a slot 6 provided in the tube 3 adjoining its lower end, in order that the catch may engage the tube 70 to normally lock the handle section against removability, unless the catch 5 is depressed or disengaged from the tube. The adjoining sections 1 and 2 have secured thereto the cushions 7 which may be of leather, rubber or other resilient compressible material, the cushions 7 being adapted to abut tightly 75 when the sections of the staff are engaged to the tube. The section 1 carries a spring catch 8 engageable through a slot 9 provided in the tube 3 adjoining its upper end, and is further provided with an upwardly facing spring catch 10 passing through an elongated slot 11 provided in the tube 3 intermediate its ends, the slots 6, 9 and 11 80 85 all being on the same side and in alinement.

The ribs are pivoted to the main section 1 of the staff as usual, the upper end of the tube 3 being normally spaced below the pivotal point of the ribs. Each rib embodies an inner pivoted section 12 and an outer sliding section 13, the section 12 being U-shaped in cross section and the section 13 being circular in cross section, and preferably solid. The section 13 telescopes 90 into the section 12, the outer end of the section 12 being provided with a pair of lips 14 bent or struck toward each other so as to completely embrace the section 13. The inner end of the section 13 is bent back 95 through the slot provided in the section 12 as denoted by the numeral 15, and the said end is also bowed toward the body of the section 13 as designated by the numeral 16. The slot provided between the edges of the 100 section 12 is slightly narrower in width than the diameter of the section 13, so that the section 13 may be snugly retained within the section 12, the bight provided by the reflexed end 15 being provided with the opposite 105 grooves 23 engaged by the edges of the section 12. The reflexed end 15, or

rather the bowed portion 16, is flattened and adapted to snap over the lips 14 as the rib is extended and retracted.

The stretchers 17 are pivoted to the runner 18 slideable on the tube 3, and are pivoted to their outer ends to terminal eyes formed on the respective reflected ends 15 of the outer or sliding sections of the ribs, the outer ends of the stretchers 17 being bifurcated or forked so as to straddle the reflexed ends 15, and rivets or pivot pins 20 being passed through the bifurcated portions 19 and the eyes of the reflexed ends 15. Braces 21 are pivoted to the upper end of the tube 3 and their outer ends are pivoted to intermediate points of the stretchers 17 by means of clamps 22 embracing the stretchers 17 and to which the braces 21 are pivoted.

The parts of the umbrella as thus described, may be readily and inexpensively manufactured and assembled, the present umbrella construction being simple, durable and compact as well as convenient, efficient and serviceable in its use.

In use, it being understood, of course, that the textile or fabric covering is attached to the respective sections of the ribs, the handle section 2 is engaged within the lower end of the tube 3, and the downwardly facing catch 8 is engaged through the slot 9 of the tube 3, so that the cushions 7 will abut tightly in order to hold the staff sections in position relative to each other so as to eliminate rattling and other objectionable qualities. The runner 18 is engageable by the catch 10 so that the stretchers 17 maintain the sliding sections 13 of the ribs extended or projected. It will be noted that the catch 10 also engages the upper end of the slot 11 (see Fig. 8) so as to lock the upper section of the staff against moving upwardly relative to the tube 3, so that the frame work will be substantial and will not be liable to collapse accidentally. When the sections 13 of the ribs are extended, the portions 16 of the reflexed ends 15 will snap over and project beyond the outer ends or lips 14 of the sections 12, the reflexed ends being resilient to permit a slight yielding action which is desirable.

When it is desired to fold or collapse the umbrella, the catch 10 is pushed inwardly so as to release the runner 18, and the runner 18 may then be started downwardly on the tube 3, the catch 8 being pressed inwardly so as to release the tube 3. The runner 18 being slid downwardly will cause the outer ends of the stretchers 17 to be swung toward the staff with the braces 21, and consequently, the ribs will not only be folded toward the staff, but will be telescoped, the outer sections 13 being slid into the sections 12, as seen in Fig. 5. When the outer sections of the ribs are thus slid inwardly, the reflexed ends 15 are snapped inwardly over

the lips 14 thus permitting the ribs to telescope, the notches 23 engaging the edges of the sections 12, however, to prevent the inner ends of the sections 13 from springing out of engagement with the sections 12. After the parts have been folded to their initial or primary folded position, the handle section 2 is detached by disengaging the catch 5 from the tube 3, and the tube may then be slid upwardly on the main section 1 so as to further telescope the outer sections of the ribs into the inner sections as seen in Fig. 6. The reflexed ends 15 of the outer sections 13 also permit the parts to fold together compactly and within a small compass, so that the umbrella may be readily carried within a suitcase, traveling bag, or the like.

The catch 5 is so positioned, that when the runner is slid downwardly to fold the relative parts, the runner is engaged by the catch 5, so as to lock the parts against further movement unless the catch 5 is released. This is desirable when the handle section is not to be removed, so that the umbrella may be carried by hand without the ribs opening.

The umbrella may be readily opened by an operation reverse to that above described, as will be apparent, the up and down movement of the runner 18 on the tube 3 serving to extend and retract the outer or sliding sections of the ribs and unfold or fold the umbrella.

Having thus described the invention, what is claimed as new is:—

1. In an umbrella, a two part staff, a tube slideable on one part, collapsible ribs pivoted to the said part, a runner slideable on the tube, stretchers connecting the runner and ribs, the other part of the staff being insertible into the tube, catches carried by the parts of the staff and engageable with the tube, cushions attached to the adjoining ends of the parts and adapted to abut tightly when the respective catches are engaged to the tube.

2. In an umbrella, a staff embodying a main section and a removable handle section, a tube slideable on the main section, the handle section being insertible into the tube, each of the sections of the staff having a catch engageable with the tube to lock the sections together, the tube having an intermediate elongated slot, a second catch carried by the main section of the staff and engaging through the said slot, telescopic ribs pivoted to the main section of the staff, and a runner slideable on the tube and operatively connected to the ribs, the runner being engageable by the last mentioned catch when raised and being engageable by the catch of the handle section when lowered.

3. In an umbrella, a rib embodying a pivoted U-shaped section and a sliding sec-

tion telescoping thereinto, the pivoted section having means at its outer end for completely embracing the sliding section, the inner end of the sliding section being re-
5 flexed, the reflexed end being curved to snap over the said means and a stretcher pivoted to the said reflexed end.

In testimony that I claim the foregoing as my own, I have hereto affixed my signature in the presence of two witnesses.

JOHN MITCHELL BEAVER.
